ROBERT A. EGRESMAN, OF MOORE, PENNSYLVANIA, ASSIGNOR TO WESTINGHOUSE ELECTRIC AND MANUFACTURING COMPANY, A CORPORATION OF PENNSYLVANIA.

STOKER STRUCTURE.

Application filed April 18, 1922. Serial No. 554,518.

This invention relates to mechanically operated furnaces having a refuse pit for the removal of solid products of combustion, and more particularly to means for treating the residuum of the fuel discharged from the active grate surfaces prior to its removal from the refuse pit. It has for an object to provide an apparatus of the character designated which shall prevent the formation of objectionable clinker masses in or above the refuse pit.

The term "refuse" in the specification and claims of this application is employed in a generic sense to include the residuum of fuel discharged from the active grate surfaces.

In mechanically operated furnaces of steam power plants in which high furnace temperatures are normally maintained and in which fuels of low fusibility are employed, objectionable clinker masses tend to form over and in the refuse pit, which clinker masses prevent the complete combustion of the unburned content of the refuse, both by occluding the unconsumed carbon and by interfering with the uniform distribution of air through the refuse, and under conditions favorable for the adhesion of clinkers, clinker masses of considerable size form by accretion, which either clog or greatly increase the work of the discharge mechanism, and which not infrequently become of such size as to bridge the refuse pit.

It has heretofore been proposed to break up the clinker masses formed in and above the refuse pit by mechanical means, such as moving members operated from the stoker driving mechanism. These constructions have failed in certain installations employing low grade fuels, since, at best, they merely break up the clinker masses already formed.

It is the purpose of the present invention to overcome the difficulties above mentioned, by providing in connection with the pit a construction which prevents the formation of clinker masses in and above the refuse pit. This result is secured by the employment of a specially constructed casting over which a relatively shallow zone of high temperature combustion is maintained in the upper portion of the refuse and by the in-

jection of streams of an aqueous medium, as, for example, water or steam, into the refuse at a level well toward the top of the pit. The steam, produced by the impingement of the water upon the highly heated refuse, in case water is injected, or, directly injected into the refuse, rises upwardly through the burning residue and attacks the hot refuse, destroying its adhesive properties and making it extremely friable. The refuse in and above the pit is thus maintained in a uniformly loose and open condition, in which condition it is readily passed downwardly through the pit and removed therefrom without the difficulties commonly encountered.

These and other objects, which will be more manifest in the further description of my invention, are attained by the employment of the apparatus illustrated in the accompanying drawings in which Fig. 1 is a fragmentary longitudinal sectional view of an underfeed stoker embodying my invention; Fig. 2 is a view, in elevation, of a specially constructed air box having provision for carrying the distributing header; and Fig. 3 is a sectional view of the air box shown in Fig. 2.

Referring to Fig. 1, I show an underfeed stoker 10 of the single-end type, having alternate series of tuyères 11 and intervening retorts 12, the tuyères being mounted on the air chambers 13 which also serve to form the side walls of the retorts 12. At the lower end of the tuyères and retorts are dead plates 14 over which the residuum of the fuel passes from the active grate surface to the refuse-discharge pit 15. The pit 15 extends the full width of the furnace and has at its bottom suitable refuse-discharge mechanism 16, which may be of any well known type.

The front wall of the pit has at its upper portion sectionally-constructed air boxes 20, preferably secured to the air chambers 13 and communicating therewith through openings 21. Each air box section (Figs. 2 and 3) has a cross sectional configuration particularly adapted for securing the advantageous combustion conditions above described. The sections may be cast integrally or may be made, for convenience of manufacture and assembly, of a number of cast

ings. As shown, each section comprises three castings, 22, 23 and 24. The casting 22 is in the form of an obtuse angle and has a vertical face 25 abutting against a corresponding face of the wind box 13, the other face 26 forming the bottom of the box 20.

The casting 23 is the refuse-supporting member of the box and has an upper horizontal face 28 extending inwardly beneath and beyond the dead plate 14, an inclined-exposed face 29 sloping downwardly and inwardly from the inner edge of the upper face toward the center of the pit and at a somewhat larger angle of inclination to the horizontal than that of the inclination of the tuyères. In the face 29 are a plurality of air-delivering apertures 30. A curved re-entrant face 31 extends downwardly from the lowermost edge of the fuel-supporting face 29.

The casting 24 is a triangularly-shaped casting which depends beneath the extending face 29 of the casting 23 and is provided with a hook 32 coacting with a bracket 33 cast integrally with the member 23. The exposed face 34 of the casting 24 is substantially vertical, and is preferably slightly curved downwardly and outwardly from the lower edge of the extending face 29, as shown. The casting 24 serves as a guide for the refuse, which more readily passes downwardly through the pit because of the receding face 34. Downwardly-extending apertures 35 are also provided in the casting 24. The castings 23 and 24, when assembled, form between them an inwardly-opening chamber 38 for the reception of a distributing header 39, which is adapted to discharge jets of aqueous medium through apertures 40 and an opening 41 between the castings 23 and 24 into the refuse pit. Beneath and substantially in vertical alignment with the air box 20 are sectional guide plates 42.

Apron sections 45 pivotally supported at their upper ends 46 in any suitable manner, as from brackets 47, secured to the frame of the furnace, are disposed beneath the guide plates 42 and co-operate with the plates 42 to guide the refuse to the discharge mechanism 16. The latter construction forms no part of the present invention, and for this reason a detailed description thereof is deemed unnecessary in the present specification.

The rear wall of the pit comprises a bridge wall 52 of refractory material supported on a hollow base plate 53 which may be mounted on the framework of the furnace. An air box 54 is disposed beneath the base plate 53 and opposite to the guide plate 42. Apertures 55 on the exposed surface 56 of the box 54 deliver air to the combustion zone of the pit. An apron 57, in all respects like the apron 45, forms the lower portion of the rear wall of the pit. It may be desir-

able to employ sprinkler heads 60 on each side of the pit and immediately above the aprons for thoroughly quenching the refuse in the bottom of the pit, although it is to be understood that the headers 60 are in no wise essential to the proper functioning of the apparatus comprising my present invention.

The manner of operation of the above described apparatus is as follows: The residuum of the burning fuel passes downwardly from the active grate surface, composed of alternate series of tuyères and retorts, over the dead plates 14 into the pit 15. Assuming that the furnace is in full operation, the refuse gradually removed from the bottom of the pit causes the refuse thereabove to slowly move downwardly in the pit. The fuel bed in and over the pit is, however, so maintained that there is at all times a considerable thickness of residuum over the dead plates 14 and the air boxes 20. Air, preferably under pressure, is delivered into the refuse from the boxes 20 and maintains an active combustion in the upper portion of the pit. While the refuse in its downward passage is being supported on the face 29 of the box 20, and as it passes below the level of the header 39, an aqueous medium, which may be water, steam, a mixture of water and steam, or a mixture of water and air, is injected from the headers into the refuse. There results sudden absorption of the heat of the refuse, resulting in a rapid rise in temperature of the aqueous medium and, in case the water is employed, a copious generation of steam. The aqueous medium upon injection and during its upward passage through the refuse contacts intimately therewith and acts directly thereon to destroy the adhesive properties of the clinker or slag content thereof. This action of the aqueous medium upon the refuse results in the prevention of the formation of objectionable clinker masses in the refuse.

A wide temperature difference between the highly heated refuse and the injected fluid serves to augment the active interaction between the refuse and the aqueous medium. It is, consequently, desirable to maintain a high temperature of the refuse into which the aqueous medium is injected. The water box 20 disclosed herein is, therefore, constructed to support the refuse upon its upper face 29 and at the same time maintain a high rate combustion thereover by supplying air under pressure to the refuse supported on the upper face 29. The heated clinker or slag content of the refuse has a tendency to agglomerate as it passes over the inner edge of the face 29 into the pit. At these points of incipient slag formation, the streams of aqueous medium are injected into the heated refuse. There results an intimate contact and active interaction between the clinker and the aqueous medium which

effectually destroys the agglomerating properties of the refuse.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a furnace, in combination in an ash discharge device therefor, a pit adapted to receive the refuse from the active grate surface comprising an air box forming an upper portion of one of the side walls of the pit and having a chambered recess in a wall thereof exposed to the refuse, and means within said recess for discharging jets of a cooling fluid into the refuse.
  2. In a furnace, in combination, an ash discharge device therefor, a pit adapted to receive the refuse from the active grate surface comprising an air box forming the upper portion of one of the side walls of the pit and having a horizontally extending recess in the wall thereof exposed to the refuse, a header disposed within the said recess and arranged to discharge jets of water into the refuse.
  3. In a furnace, the combination with an ash discharge device having a pit to receive refuse from the active grate, of an air box forming an upper portion of the side wall of the pit, said air box comprising an exposed declined top wall provided with air emitting apertures, a re-entrant side wall lying beneath the top wall and forming a chamber for the disposition of a fluid distributing header, and an angular supporting wall portion cooperating with said top and side walls to form a box-like air chamber.
  4. In a furnace, the combination with an ash discharge device having a pit to receive refuse from the active grate, of an air box forming an upper portion of the side wall of the pit, said air box comprising an exposed declined top wall, provided with air emitting apertures, a re-entrant side wall lying beneath the top wall and forming a chamber for the disposition of a fluid distributing header, an angular supporting wall portion cooperating with said top and side walls to form a box-like air chamber, and a guide wall supported on the side wall and spaced from and oppositely declined to the top wall.
  5. In a furnace, the combination with an ash discharge device having a pit to receive refuse from the active grate, of a sectional air box forming an upper portion of the side wall of the pit, each section of said air box comprising an exposed declined top wall provided with air emitting apertures, a re-entrant side wall lying beneath the top wall and forming a chamber for the disposition of a fluid distributing header, and an angular supporting wall portion cooperating with said top and side walls to form a box-like air chamber.
- provided with air emitting apertures, a re-entrant side wall lying beneath the top wall and forming a chamber for the disposition of a fluid distributing header, and an angular supporting wall portion cooperating with said top and side walls to form a box-like air chamber.
6. In a furnace, the combination with an ash discharge device having a pit to receive refuse from the active grate, of a sectional air box forming an upper portion of the side wall of the pit, each section of said air box comprising an exposed declined top wall provided with air emitting apertures, a re-entrant side wall lying beneath the top wall and forming a chamber for the disposition of a fluid distributing header, an angular supporting wall portion cooperating with said top and side walls to form a box-like air chamber, and a guide wall supported on the side wall and spaced from and oppositely declined to the top wall.
  7. In a furnace, the combination with an ash discharge device having a pit to receive refuse from the active grate of an air box forming an upper portion of the side wall of the pit, said air box comprising a protruding declined top wall, a receding guide wall, and means for introducing streams of aqueous medium from the air box into the pit at the juncture of said top and guide walls.
  8. In a furnace, the combination with an ash discharge device having a pit to receive refuse from the active grate, of an air box forming an upper portion of the side wall of the pit, said air box having a re-entrant chamber for housing a distributing header.
  9. An air box for a refuse pit comprising a fuel supporting portion having a re-entrant chamber therein for housing a fluid distributing header.
  10. An air box for a refuse pit comprising fuel supporting portions having a re-entrant chamber therein for housing a fluid distributing header, and including a protruding declined top wall, and a guide wall joined to the lower edge of the top wall and forming therewith an overhanging ledge.
  11. An air box for a refuse pit comprising fuel supporting portions having a re-entrant chamber therein for housing a fluid distributing header, and including a protruding declined top wall and a guide wall receding from the line of juncture with the top wall.
  12. An air box for a refuse pit comprising an exposed declined top wall provided with air emitting apertures, a re-entrant side wall lying beneath the top wall and forming a chamber for housing a fluid distributing header, and an angular supporting wall portion cooperating with said top and side walls to form a box-like air chamber.

13. An air box for a refuse pit comprising an exposed declined top wall provided with air emitting apertures, a re-entrant side wall lying beneath the top wall and forming a chamber for housing a fluid distributing header, and an angular supporting wall portion cooperating with said top and side walls to form a box-like air chamber, and a guide wall supported on the side wall and spaced from and oppositely declined to the top wall.

14. A sectional air box for a refuse pit each section comprising an exposed declined top wall provided with air emitting apertures, a re-entrant side wall lying beneath the top wall and forming a chamber for housing a fluid distributing header, and an angular supporting wall portion cooperat-

ing with said top and side walls to form a box-like air chamber.

20

15. A sectional air box for a refuse pit, each section comprising an exposed declined top wall provided with air emitting apertures, a re-entrant side wall lying beneath the top wall and forming a chamber for housing a fluid distributing header, an angular supporting wall portion cooperating with said top and side walls to form a box-like air chamber, and a guide wall supported on the side wall and spaced from and oppositely declined to the top wall.

25

In testimony whereof, I have hereunto subscribed my name this 14 day of April 1922.

ROBERT A. FORESMAN.
